Primary Examiner — Rashida C. Walshon(74) *Attorney, Agent, or Firm* — Edell, Shapiro & Finnian, LLC(57) **CLAIM**

The ornamental design for a shoe upper, as shown and described.

DESCRIPTION

FIG. 1 is a front and lateral side view in perspective of a shoe upper showing my new design;

FIG. 2 is a lateral side view thereof;

FIG. 3 is a medial side view thereof;

FIG. 4 is a top view thereof;

FIG. 5 is a bottom view thereof;

FIG. 6 is a front view thereof; and,

FIG. 7 is a rear view thereof.

The shoe upper illustrated is a first embodiment showing a right-footed form of the shoe upper. A second embodiment is for the left-footed form of the shoe upper, which is a mirror image of the right-footed form, is not illustrated. The broken line illustration in the drawings is not part of the claimed design. The dot-dash line illustration in the figures defines the bounds of the claimed design and forms no part thereof.
